(57) **CLAIM**

The ornamental design for a head of a pneumatic tool, as shown.

DESCRIPTION

FIG. 1 is a perspective view of a head of a pneumatic tool showing a new design;

FIG. 2 is a top view thereof;

FIG. 3 is a bottom view thereof;

FIG. 4 a right side view thereof;

FIG. 5 is a left side view thereof;

FIG. 6 is a front view thereof; and,

FIG. 7 is a back view thereof.

The broken lines in the Figures are for illustrative purposes only and form no part of the claimed design.
